TERRY WARP STOP MOTION

Charles E. Whittaker, Galt, Ontario, and George G. Slough, St. Catharines, Ontario, Canada

Application April 14, 1943, Serial No. 483,020

7 Claims. (Cl. 139—353)

Our invention relates to looms, and has among its objects and advantages the provision of an improved terry warp stop motion attachment. So far as we are aware, no suitable warp stop motion has been devised for automatically stopping a loom using terry when a top or terry warp end is broken. Since the pile warps become loose when the pile pick is woven in at the fell of the cloth, present types and styles of drop wires are not suitable. In the present invention, the drop wire is lifted up when the pile pick is woven in at the fell of the cloth, thereby disengaging the drop wires on the pile pick, and allowing the attachment to function on the remaining picks which are woven with tight pile warp ends.

In the accompanying drawings:

Figure 1 is a side view of a loom structure illustrating our invention applied thereto.

Figure 2 is an elevational view illustrating an operating linkage.

Figure 3 is a top view of the structure of Figure 2.

Figure 4 is a view illustrating an adjustable rod link.

Figure 5 is a view of an adjustable rod link coacting with the structure of Figure 4.

Figure 6 is a sectional view along the line 6—6 of Figure 5.

Figure 7 is a detail view of a link pivot and turnbuckle.

Figure 8 is a sectional view along the line 8—8 of Figure 7.

Figure 9 is a detail view of a slidable pivot.

Figure 10 is a view of the pivot of Figure 9 but rotated 90 degrees about its axis, and

Figure 11 is a view of one of the drop wires.

In the embodiment of the invention selected for illustration, Figure 11 illustrates a drop wire 12 provided with slots 14 and 16 in the manner of conventional drop wires. This drop wire is formed to provide a slotted extension, that is, is of greater length than the conventional drop wire and is provided with a third slot 18 elongated longitudinally of the wire and above the conventional slots 14 and 16. Figure 11 illustrates a gang of drop wires 12 in association with an electric circuit 20 and a controller 22 along the lines of that illustrated in Patent No. 1,832,580, issued November 17, 1931. Two parallel rods 24 extend through the slots 18, which rods are connected into the electric circuit 20, as by the wires 26.

Figure 1 illustrates the bottom beam end at 28 and the top beam end at 30.

In Figures 2 and 3, the rods 24 are supported in blocks 32 through which the rods are extended. The blocks 32 are suspended from two arms 34 and an intermediate arm 36 through the medium of rods 38 and 40, respectively.

Figure 4 illustrates one of the rods 38 in connection with its respective block 32, the two rods and blocks being identical. The rod 38 has a threaded end 42 threaded in a bore 44 in the block 32 and has a nut 46 thereon engageable with the top face of the block for locking the rod on the block. Set screws 48 are threaded into the block 32 for engagement with the rods 24.

The rod 40 has an end 50 threaded through the bight 52 of a U-shaped member 54 having openings 56 in the ends of its legs for connection with the rods 24. A lock nut 58 is threaded on the end 50 to engage the bight 52. The upper ends of the rods 38 and 40 are similarly connected with their respective arms 34 and 36. Figure 6 illustrates one such connection. A pin 60 extends loosely through an opening 62 in the flattened rod end 64. This end lies adjacent a flange 66 attached to the pin 60, and the end is held on the pin by a cotter pin 68.

The pin 60 is provided with a body 70 slidable in a slot 72 in the arm 34. A nut 74 is threaded on the opposite end of the pin 60 to hold the arm 34 between the flange 66 and a washer 76 mounted on the pin adjacent the nut 74.

All the arms 34 and 36 are fixedly connected with a shaft 78 mounted for oscillation in bearings 80 carried at the outer ends of arm-like brackets 82 bolted at 84 to the loom frame 86. To the shaft 78 is fixedly connected an arm 88 which is oscillated through the medium of a lift rod 90 connected with an arm 92 attached to the pile shaft 94. This shaft is oscillated through the medium of an arm 96 and an actuating cam 98.

Figure 7 illustrates the pivotal connection between the upper end of the lift rod 90 and the arm 88, the pivotal connection between the lower end of the lift rod and the arm 92 being the same. A turnbuckle 100 is threadedly connected with the rod 90 and fixedly related thereto by a lock nut 102. This turnbuckle includes a flat end 104 having an opening 106 for pivotal reception of a pin 108. The end 104 lies adjacent a flange 110 on the pin 108 and is held on the pin by a washer 112. This washer is held in place by a cotter pin 114. A flattened body 116 is formed on the pin 108 for slidable reception in a slot 118 in the arm 88. The arm is held between the flange 110 and a nut 120 threaded on the pin 55.

108. Corresponding reference characters are applied to the lower pivotal connection of the lift rod 90.

The extra slot provided in the upwardly directed longitudinal extension of the drop wire 12 permits the drop wire to be lifted when the terry loom is operating on the loose pick or pile pick of the terry warp, thereby disengaging the pile drop wires from forming contact with the mechanical or electrical stop motion.

The pins 60 may be shifted to different positions longitudinally of the arms 34 and 36 and secured in such positions through tightening of the nuts 74. The flattened ends 64 pivot freely on the pins. The pin 108 is also adjustable to 15 different positions longitudinally of its respective arm and may be fixedly secured against shifting through tightening of the nut 120.

Without further elaboration, the foregoing will 20 so fully explain our invention that others may, by applying current knowledge, readily adapt the same for use under various conditions of service.

We claim:

1. In a terry loom having a stop motion including drop wires, a terry warp stop motion comprising a slotted extension on said drop wires, rods extending through said slotted extensions, a rock shaft, arm means fixed to said rock shaft and having an operating connection with said rods to raise and lower the latter through rocking motion of said rock shaft, and means for rocking said rock shaft, said slotted extensions allowing the drop wires to be lifted when the loom is operating on the loose pick or pile pick of the terry warp to bring the drop wires out of contact with said first mentioned stop motion.

2. The invention described in claim 1 wherein in said last mentioned means comprise a loom pile shaft, an arm attached to the pile shaft, a second arm fixed to said rock shaft, and a link connecting the second arm with the arm on the pile shaft.

3. The invention described in claim 1 wherein in said arm means comprise a plurality of arms, and in which said operating connection comprises

links respectively connecting the arms with said rods.

4. The invention described in claim 1 wherein blocks carry said rods, said arm means comprising arms attached to the rock shaft, and links connecting said arms with said blocks.

5. The invention described in claim 1 wherein in said arm means comprise three arms fixed to the rock shaft, two blocks carrying said rods, links attached to the respective blocks and pivotally connected with two of said three arms, and an operating connection between the third arm and said rods.

6. The invention described in claim 1 wherein in said last mentioned means includes a rotary loom pile shaft, a rotary cam having an operating connection with said pile shaft to rock the latter, a pile shaft arm, a lift rod pivotally connected at one end with said pile shaft arm, and an arm fixed to said rock shaft and pivotally connected with the opposite end of said lift rod.

7. In a terry loom having a stop motion including drop wires, a terry warp stop motion comprising a slotted extension on said drop wires, rods extending through said slotted extensions, a rock shaft, a plurality of arms fixed to said rock shaft, links attached to said rods and having pivotal connections with the respective plurality of arms, said pivotal connections being adjustable longitudinally of said plurality of arms, said rods being raised and lowered through rocking motion of said rock shaft, a loom pile shaft having a pile shaft arm, a fourth arm fixed to said rock shaft, a lift rod having pivotal connections with said pile shaft arm and said fourth arm, said latter mentioned pivotal connections being adjustable longitudinally of their respective arms, and cam means for imparting rocking motion to said pile shaft, said slotted extensions allowing the drop wires to be lifted when the loom is operating on the loose pick or pile pick of the terry warp, to bring the drop wires out of contact with said first mentioned stop motion.

CHARLES E. WHITTAKER.
GEORGE G. SLOUGH.
